THERMOSTAT

Howard D. Matthews, Minneapolis, Minn., assignor to Minneapolis-Honeywell Regulator Company, Minneapolis, Minn., a corporation of Delaware

Application April 11, 1940, Serial No. 329,125

2 Claims. (Cl. 297—16)

The present invention relates to motion compensating means for a condition responsive device, and more particularly to the structure of such a device.

Condition responsive devices, and more particularly bimetallic temperature responsive elements, which are subjected to mediums which contain impurities, quite frequently become sticky due to deposits of these impurities which impede the operation thereof. Particularly when the elements are confined upon sliding guides does this condition prevail. With present condition responsive elements of the compound coiled type, as shown in United States Patent No. 2,121,259, and French Patent No. 710,481, and utilized to obtain axial movement, it is usually necessary to provide such sliding guides to prevent rotation of the element. These guides not only become sticky because of continued exposure to impurities, but in many adaptations appreciably reduce the efficiency of the element, even when perfectly clean, because of sliding friction.

It is an object of this invention to obtain optimum efficiency in a compound coiled, axially movable condition responsive element, by compensating for angular movement thereof.

Further objects will become apparent from a perusal of the accompanying specification and the appended claims.

In the drawing:

Figure 1 is an elevational view of any device, Figure 2 is an end view looking at the left end of Figure 1, and

Figure 3 is a diagrammatic view to illustrate the method of computing linear movement of a compound helix.

Referring now more particularly to the drawing. The condition responsive element is shown as comprising a compound coiled helix generally indicated by the reference character 10. Ends 11 and 12 are provided and are adapted to compensate the center portion 10 for angular movement upon changes in the condition to which the element responds. The entire element is composed of two metals having different coefficients of expansion which are suitably secured together. Such material is conventionally known in control art as bimetal and in the present instance is made of brass and invar iron suitably welded together. The brass is the high expansion metal and the invar iron is the low expansion metal. However, many other metals may be used without departing from the spirit of the present invention.

The compound helix 10 is composed of a series 55

of minor convolutions A, B, etc. to Y and Z. The minor helix is then wound into a major helix. As shown in the drawing, the minor helix is right-hand wound the the major helix is left-hand wound. It will also be noted that the two arcuate ends 11 and 12 are also left-hand wound. A motion takeoff arm 13 is provided on the end 12, and a suitable mounting arm 14 is formed from the other compensating end 11.

In winding the compound coiled member there are three factors to be considered: The first factor concerns the side of the minor convolutions which is the high expansion metal. If the high expansion metal is on the inside of the minor convolutions, these convolutions will expand when heated, and if on the outside, these convolutions will contract when heated. The second factor concerns the direction in which the minor helix is wound. If the minor helix is right-hand wound, and the interior metal of the bimetal is the high expansion metal, the helix will rotate angularly in a counter-clockwise direction when heated; and if left-hand wound, the rotation will be clockwise. Obviously, if the high expansion metal were placed on the outside of the minor convolutions, the direction of rotation thereof would be reversed for the right or left hand directions of the wind of the helix. The third factor concerns the direction in which the major helix is wound and, in combination with the other two factors, determines the angular direction of movement of the entire portion 10 of the temperature responsive element. It will be more fully described later, that when any one of these three factors is reversed, the axial movement of the element will be reversed. It will be obvious that if two factors are changed, the axial movement will not be changed.

Assume for example, that the interior metal of the bimetal is the high expansion metal and the exterior metal is the low expansion metal, the minor helix being right hand wound and the major helix being left hand wound, as shown. Upon an increase in heat the convolutions A to Z will tend to open up. It is a well known phenomenon in a single bimetallic helix that the expansion is in two directions, that is, the convolutions tend to rotate and increase in diameter, and the helix tends to elongate axially. Therefore, upon an increase in temperature the first convolution A of the minor helix will expand and this expansion will move the second minor helix B toward the right as viewed in Figure 1. In this manner each of the convolutions in the entire compound helical member 10 will move an

increment toward the right until the convolutions Y and Z of the minor helix are moved a substantial distance in this direction. For practical purposes the degree of axial movement may be computed by considering the expansion of only one of the convolutions of the minor helix as it would be plotted from a projection of a cross section of one convolution taken perpendicular to the longitudinal axis thereof. It has been found that the opposite convolution of the major helix will be moved a distance corresponding to the distance which it would have been moved by the minor convolution if the connecting convolutions were considered as being a link. To more clearly disclose this principle of computation a diagrammatic Figure 3 is shown in the drawing. In this figure a convolution c may, for practical purposes, be considered as mounted upon a fixed support d. The free end of the minor convolution c carries a link e which is connected to an upper convolution f and separates the two convolutions a distance equal to the diameter of the major helix. In the position shown in full lines for the link e the bimetallic members are in their cold position. When the convolutions of the temperature responsive element heat up the link e might be assumed to move through an angle x for a given temperature change and will assume the dotted line position e'. Therefore it is seen that the upper convolution f is moved through an angle which a single bimetal c would impart to the convolution f if the convolution c were considered as a simple bimetal loop and the connection e were a solid link. The upper convolution f for the same temperature change will expand an amount substantially equal to the amount of expansion of the convolution c, hence a lower convolution connected to the convolution f would be moved in a straight line substantially perpendicular to the link e. It will be seen that the expansion of a complete convolution of the major helix of the temperature responsive element may be computed by plotting the movement which would be imparted by a single minor convolution in moving an upper convolution a distance corresponding to a distance that the upper convolution would be moved if the two convolutions were rigidly connected by means of a link.

When the temperature responsive element 10 is subjected to a rising temperature the convolution A will axially elongate, hence moving the convolution B a slight distance away from the convolution A. Likewise each of the convolutions in the minor helix from A to Z will separate from each other, and the entire minor helix will be substantially elongated. This elongation will result in a wrapping up movement in the convolutions Y and Z assuming that the mounting arm 14 is securely fixed. In addition to the angular movement caused by the minor helix there is also a substantial angular movement inherent in the major helix.

To compensate for the angular movement of the compound helix 10 the arcuately shaped bimetallic pieces 11 and 12 are disposed at either end thereof and have the high expansion metal also on the inside of the convolution to impart an unwrapping movement to the entire element upon an increase in temperature. It will be understood that although ends 11 and 12 are both so adapted, that only one portion of the bimetal would actually need to be used to compensate the compound coil 10.

Upon cooling of the bimetallic element the reverse of the above described action will occur.

As has been previously pointed out, the minor helix A to Z is right-hand wound. As a result of its being right hand wound the movement of each of the convolutions A to Z upon being heated was toward the right in respect to each other. It will be obvious, then, that if the convolutions are left hand wound the movement with respect to each other would be toward the left and the entire element 10 will contract axially. Whether the convolutions are either right or left hand wound the angular or rotative movement of the element 10 as a result of temperature changes will be identical. If the high expansion metal is placed on the outside of the minor helix the action of the element 10 will also be reversed. The rotation of the element will likewise be in the opposite angular direction. However, if the minor helix is so wound, then the compensating ends will also have the high expansion metal on the outside and the element 10 will be compensated for rotative movement. Hence it is seen that the compensating ends 11 and 12 can compensate for angular movement of the compound helix whether it is adapted to expand or contract axially upon a given temperature change. If the major helix is right hand wound instead of left hand wound, as shown, the angular movement of the compound coil 10 will be reversed. However, the compensating ends will also be reversed in the direction of wind and, hence, will compensate for angular movement of the temperature responsive element.

For the purpose of enabling others to practice my invention the accompanying chart is presented to show various forms which my temperature responsive element may take:

Thermostatic bimetal double helices

	High Ex. Side	Minor helix winding	Major helix winding	Movement with increase of temperature	
				Axial	Angular
45	1 Outside	R. H.	R. H.	Open	Unwinds.
	2 Outside	R. H.	L. H.	Close	Winds.
	3 Outside	L. H.	R. H.	Close	Unwinds.
	4 Outside	L. H.	L. H.	Open	Winds.
	5 Inside	R. H.	R. H.	Close	Unwinds.
	6 Inside	R. H.	L. H.	Open	Winds.
	7 Inside	L. H.	R. H.	Open	Winds.
	8 Inside	L. H.	L. H.	Close	Unwinds.

It will be noted that when different elements of the bimetal are reversed that the axial movement of the element is reversed and that also the winding or unwinding of the major helix is also effected. Where a very active element is desired either of the types shown in 1 or 2 of the accompanying chart may be used. These bimetals will be very sensitive to temperature changes inasmuch as the high expansion metal is on the outside of the minor helix and hence more exposed to the current of heated air or other medium to which the entire element is subjected. It will be noted that the type 1 opens when heated and type 2 closes when heated. If slow responsive elements are desired either of the types 5 or 6 might be used where the high expansion metal is located on the inside of the minor helix, therefore making the helix respond more slowly to temperature changes. Other types may be selected as desirable for the uses to which they are to be put. In all of the types charted there is an angular rotation of the double helix, the direction of which is shown so that proper compensation may be provided.

While I have shown and described one form which my invention may take it will be apparent that many changes will occur to those skilled in the art. Therefore it is to be clearly understood that I am to be limited only by the scope of the appended claims.

I claim as my invention:

1. A device of the character described comprising a bimetal strip with a first portion of minor convolutions wound into major convolutions, and a second portion of said strip continuing from an end of said first portion wound into a helix in the same direction as said major convolutions, said first portion being movable axially and angularly in a first direction upon heating, and said second portion being movable angularly in the opposite direction upon heating to compensate said first portion for angular movement.

2. A device of the character described comprising a bimetal strip of first and second metals having different properties of thermal expansion, a first central portion of said strip being of minor convolutions wound into a helix of major convolutions, the first of said metals being on the outside of said minor convolutions, and second and third portions of said strip continuing from the ends of said first portion, said second and third portions being wound in convolutions in the same direction as said helix and having said first metal on the outside of said convolutions, said first portion being movable axially and angularly in a first direction on heating, and said second and third portions being movable angularly in the opposite direction upon heating to compensate said first portion for angular movement.
